UNITED STATES PATENT OFFICE.

AARON K. KLINE, OF READINGTON, NEW JERSEY.

IMPROVEMENT IN CAR-COUPINGS.

Specification forming part of Letters Patent No. **136,655**, dated March 11, 1873.

To all whom it may concern:

Be it known that I, AARON K. KLINE, of Readington, in the county of Hunterdon and State of New Jersey, have invented a new and Improved Car-Coupling, of which the following is a specification:

The invention is an improvement on my patent granted March 5, 1872; and consists in cutting away the rear wall and forming a backwardly-inclined plane to receive and conveniently hold the coupler.

Figure 1 is a longitudinal sectional elevation of the draw-heads of a couple of cars constructed according to my invention. It also represents the coupling-rod in side elevation, and in the position it occupies when the cars are coupled. Fig. 2 is a plan view, and Fig. 3 is a sectional elevation of one of the draw-heads, and side elevation of the coupling-rod as in its adjustment for self-coupling. It also shows the coupling-rod in dotted lines in the cavity behind the coupling-shoulders when the cars are not coupled.

Similar letters of reference indicate corresponding parts.

A represents the draw-head with the three-sided opening in the end to admit the end of the headed coupling-rod D, which is forced up the sides and passes into the cavity F behind the shoulders E, to be engaged by them when the part of the rod which joins the head falls in the narrow space between the walls C and rests upon the upper end of the bottom wall B. G is a notch in the back wall of the cavity F at the bottom, to receive the projection H of the coupling-rod to hold the latter, as represented in Fig. 3, for coupling self-actingly. Heretofore the back wall of the cavity F has extended directly upward to the top of the draw-head, so that when the cars stood so that the buffers touched, with the projections H both under

the overhanging walls of the notches G, the rod could not be lifted out without moving the cars apart; because after lifting one end above the corner a of the said overhanging wall of one of the draw-heads, the rod being short enough for one end to pass out of its notch, the wall above would prevent the endwise movement of the coupling-rod necessary for the other end to be withdrawn from its notch G. I therefore construct these buffers without this vertical wall, except for a very short distance above the notch G, to allow of the necessary end movement, so that I can uncouple the cars readily when standing together; and I prolong the upper portion of the cavity F about the length of the coupling-rod, arranging the bottom K and deepening said cavity at L, so that the rod may be laid on said bottom with one head overhanging part L and the other the front part F of the cavity when the cars are uncoupled and be retained securely until wanted for coupling again.

By these improvements this coupling may be used for coal-cars, which, standing together in long trains, awaiting their turn for being brought to the dumping-place, sometimes require to be uncoupled without being separated; and they also require to have the connecting-rods adjusted for coupling self-actingly when separated, and before coming together, which this contrivance is particularly adapted for.

Having thus described my invention, I claim as new and desire to secure by Letters Patent—

A draw-head having rear piece K backwardly-inclined on its top surface to receive and hold the coupling-rod when not in use.

AARON K. KLINE.
